A. E. BUTTERFIELD

CHIMNEY COVER

Filed May 1, 1925

Inventor:

Andrew E. Butterfield
By ~~W. Dickinson~~ Atty.

UNITED STATES PATENT OFFICE.

ANDREW E. BUTTERFIELD, OF LA CROSSE, WISCONSIN.

CHIMNEY COVER.

Application filed May 1, 1925. Serial No. 27,208.

The invention relates to chimney covers. The object of the invention is to provide a cover for the tops of chimneys so that at desired times the flue of the chimney may 5 be closed against the admission of rains, birds, and the like, so as to protect the walls of the building from streaks caused by trickling water, and the stoppage of the flue by reason of the building of nests of birds, 10 especially during the summer time, when the chimney may not be in use, etc.

Another object of the invention is to provide such a chimney cover that shall be easy to manipulate without a person being 15 obliged to climb to the roof of the building, that will to best advantage accomplish its purpose, be easily applied to the chimney, and easily removed therefrom when desired.

In the drawings Fig. 1 is a perspective 20 view of the cover shown as applied to a chimney, the chimney being shown in dotted lines.

Fig. 2 is an end view of the cover, with 25 portions broken away, showing the cover in closed position.

Fig. 3 is an end view, showing the cover in open position.

In the drawings the numeral 10 indicates 30 a frame for the swinging top of the cover, intended to surround the top of the chimney, 11 indicates series of legs supporting the cover, the legs being pivoted at their upper ends to the frame 10. 11^a are curved or hooked ends formed at the bottoms of the 35 legs 11, for the reception of wires or other fastening means, for securing the legs to the chimney; as shown the wire being inserted in the hooks and the ends twisted together. 11^b indicates the corners of the wire 40 fasteners where they bend around the corners of the chimney. By pivoting the legs to the frame, the device may be made more compact for shipping purposes or for storage when not in working position.

The numeral 12 indicates the cover proper, 45 it being formed with side flanges or walls, and a curved top portion, to better shed rains or other things that might tend to lodge on the top of the cover. It is shown 50 as being concavo-convex in form. When in open position, as indicated in Fig. 3, the cover becomes reversed in position, and the inner hollow side is exposed to the elements. To prevent rains from accumulating in the 55 hollow of the cover, the vent 12^a is pro-

vided. When in closed position the vent being small, the possibility of passage of water therethrough is reduced to a minimum. 13 indicates the hinge by means of which the top 12 is permanently secured to the frame 10. 14 is a bracket secured to the frame, as shown, for supporting the top against undue travel when the top is opened. 15 is a spring hasp riveted to the frame 10 and extending upwardly, and provided with 60 a curved portion, formed in such shape that when the cover is closed the under side of the hasp will fit snugly against the upper portion of the top, as shown, the spring of the hasp permitting the cover to move when 65 sufficient force is exerted.

16 indicates a lever pivoted at 16^a to the forward end of an end flange of the cover, and provided intermediate its ends with the slot 16^b, the slot being placed to surround a 70 projecting pin 16^c positioned on a rear portion of the side of the frame 10. It is manifest that when the lever is rotated about its pivot the slotted portion will travel longitudinally with respect to the pivot 16^a. For 75 the purpose of opening and shutting the cover, I have provided in the free end of the lever, a ring 17, to which are secured the upper ends of suitable cords 17^a and 17^b, that are made long enough to reach to the 80 ground outside of the building, or other places where the free ends may be within easy reach for adjustment of the cover, proper hooks or other fastening means being provided (not shown) for attachment of the 85 ends of the cords. These cords so called 90 may be made of wire or other suitable material, for operating the lever.

When the cover is in open position, as 95 shown in Fig. 3 a violent wind might tend to sway the cover more or less, and to mitigate this possibility I have provided on the forward face of the cover a fastening 18, to which is secured a cord or suitable flexible device, that when the cover is open, as shown 100 in Fig. 3, may be tied or fastened to a suitable retainer to securely hold the cover in opened position. This cord 19 is an additional safeguard to the holding power of the proper cord.

It is to be noted that when the cover is 105 closed the free end of the lever passes beyond the edge of the cover to a considerable distance, so that when the cord is pulled downwardly, the lever, being fulcrumed on the 110

pin 16^a will by reason of the attachment of the lever at 16^a, cause the cover to open, and pass beyond the center of gravity so that it will tend to automatically pass to final position to rest on the bracket 14; but, also, that when opened about half way, or standing somewhat near the vertical, the cord 19 will then be in position, when pulled, to move the cover to final position shown in Fig. 3. 10 When the cover is in its opened position, and the cords are unfastened, the cords 17^a and 17^b will then be on the opposite side of the pivot or fulcrum 16^a, as shown in Fig. 3, in which case a downward pull on the cords 15 will again turn the cover on the hinge 13, but in a reverse direction, to close the cover. When, in moving in either direction, the cover reaches a neutral position, so to speak, or on a dead center relation on the hinge, 20 the cord may be moved far enough out of the perpendicular to get a side pull on the cover to draw it to opened or closed position, or so closely to final position that gravity will inevitably move it the remainder of its 25 necessary travel.

The legs 11 are made of sufficiently thin material that may be bent around projecting ornamental designs of the chimney, should such projections be high enough up 30 to come within the length of the legs, and the fastener 11^b tightened to hold the legs below the projections of the chimney.

Having now described my invention, what I claim is:

35 1. In a chimney cover, the combination of a top portion having a convex form in one direction, with flanged sides secured thereto corresponding to the shape of the top portion and with straight lower edges, a band 40 formed at its upper edge to coincide with the lower edge of the flange of the top portion and adapted to surround the sides of the top of a chimney, legs projecting downwardly from the band for vertically supporting the band adjacent the top of the chimney, means for securing the lower ends 45 of the legs fixedly to the sides of the chimney, a hinged connection between the lower edge of the top-flange and the upper edge of the band, and means for opening and closing the cover from a position removed 50 from the top of the chimney.

55 2. In a chimney cover, the combination of a band adapted to surround the sides of the top of a chimney, downwardly projecting legs for supporting the band, means for securing the legs to a lower portion of the chimney, a concavo-convex top member hinged to the band with its concave side 60 downward, a lever pivoted to the top member adjacent a portion opposed to the hinge connection, and having a fulcrumed support on the band for opening and closing the cover, and means secured to the free end of 65 the lever for operating the lever to shift the

cover from its closed and from its opened position.

3. In a chimney cover, the combination of a concavo-convex cover member having a drainage vent therethrough, a band adapted to surround the sides of the top portion of a chimney, means for supporting the band on the sides of the chimney below the band, a hinged connection between the band and the cover member, and means for operating 70 the cover member to closed and opened position. 75

4. In a chimney cover, the combination of a cover portion having an arc shaped top with side flanges therefor, a band adapted to be placed abreast of the side portions of the top of a chimney, supporting legs depending from the band adapted to be secured to the chimney below the band, a hinged connection between the flanged portion 80 of the cover top and the band and a locking connection between the cover portion 85 and the band.

5. In a chimney cover, the combination of a cover portion having a convex top and side flanges therefor, a band adapted to be placed to surround the sides of the top portion of a chimney, a hinged connection between one of the flanges and the band, a lever pivoted to the cover portion and having a longitudinally yielding support on the band, and means for operating the lever to shift the top portion to open and to closed 90 positions thereof. 95

6. In a chimney cover, the combination of a cover portion, a band adapted to be secured abreast the side portion of the top of a chimney, a lever secured to the band and to the cover portion for shifting the cover portion to opened and to closed positions, 100 an operating mechanism for opening and closing the cover depending from the lever to a position removed from the chimney and capable of being secured toward the extremity thereof when the cover is shifted, and other means secured to the cover portion for holding the cover portion in shifted position. 105

7. In a chimney cover, the combination of a cover portion having a concave under face when in closed position, and means for shifting the cover portion, the cover portion having a comparatively small water drainage aperture therein. 110 115

8. In a chimney cover, the combination of a support, adapted to be held adjacent the sides of the top of a chimney, a cover member hinged to the support, and a bracket secured to the support adapted to sustain the cover portion in its opened position. 120 125

9. In a chimney cover, the combination of a support adapted to be held adjacent the sides of the top portion of a chimney, a cover portion hinged to the support, means for shifting the cover portion to opened 130

and to closed position, a bracket on the support adapted to sustain the cover portion in its opened position, and a locking connection between the cover portion and the support adapted to secure the cover portion in its closed position.

10. In a chimney cover, the combination of a support adapted to be held adjacent the sides of the top of a chimney, a cover member hinged to the support, and a bracket adapted to sustain the cover portion in its opened position, said bracket being intermediate the cover portion and the support when the cover is open.

11. In a chimney cover, the combination of a cover portion, a support adapted to be held in juxtaposition to the upper portion of a chimney, means for supporting the first named support in its upper position comprising flexible legs depending from the first named support, and means for secur-

ing the lower portions of such legs to the sides of the chimney.

12. In a chimney cover, the combination of a cover portion, a supporting element 25 adapted to be sustained at the upper portion of a chimney, means for holding the element in its upper position comprising legs depending from the element and provided with hooked lower ends, and means 30 for engaging the hooked ends to secure the legs to the chimney.

13. In a chimney cover, the combination of a cover portion, a support for the cover portion, means for holding the support in 35 position toward the top of a chimney comprising legs pivoted at their upper ends to the support for vertical swing, and means at the lower ends of such legs for holding the legs to the sides of the chimney.

ANDREW E. BUTTERFIELD.
